UNITED STATES PATENT OFFICE.

WALTER BUTLER, OF ST. PAUL, MINNESOTA.

SUBAQUEOUS FOUNDATION AND STRUCTURE.

1,076,743.

Specification of Letters Patent.

Patented Oct. 28, 1913.

Application filed March 26, 1912. Serial No. 686,416.

To all whom it may concern:

Be it known that I, WALTER BUTLER, of St. Paul, Ramsey county, Minnesota, have invented certain new and useful Improvements in Subaqueous Foundations and Structures, of which the following is a specification.

My invention relates to sub-aqueous foundations and sub-aqueous structures and also 10 to foundations and structures above water where it may or may not be necessary or desirable to employ piling.

The object of my invention is to provide an apparatus by means of which a concrete 15 bed or structure can be formed on supporting piling or other supports, the concrete bed or structure being either entirely below the surface of the water, or entirely above, or extending partially above and below the water surface, according to the character of the work to be done.

The invention consists generally in providing a grillage adapted to rest on the tops of piles or other supports and which 25 will be embedded in and protected by the concrete entering into the structure.

Further, the invention consists in suspending a flexible fabric beneath the grillage which will sag down below and around 30 the tops of piles or other supports when the grillage is placed upon them and will conform to any inequalities in the heights or level of the supports, thus permitting the concrete to conform to any irregularities of 35 the supporting surface and form a perfect bearing for the structure to be built thereon, and, further, supporting the concrete while in plastic form, so that when the concrete is set it will inclose the upper ends of 40 the piles and effectually lock them against oscillation and also protect the metal grillage against the action of any deteriorating agencies.

In the accompanying drawings forming 45 part of this specification, Figure 1 is a perspective view illustrating the manner of filling the form supported by the piling, with concrete, Fig. 2 is a similar view, looking at the bottom of the concrete bed and illustrating the manner of filling the form with 50 concrete and the manner in which the concrete embraces and embeds the upper ends of the piles, Fig. 3 is a plan view of a portion of the form and the metal grillage 55 embodying my invention, Fig. 4 is a sec-

tional view showing the construction of the form and the manner of resting the grillage bars upon the tops of the piles, and the locking of the piles between the depending sections of the concrete bed, Fig. 5 is a 60 detail sectional view showing the pile supports, steel grillage, walls and partitions of the form, also the concrete filling which surrounds the rods forming the grillage and protects them against deterioration. It 65 also shows the flexible fabric sagging down from the load of concrete and surrounding the tops of the piles, Fig. 6 is a perspective view looking at the bottom of a portion of the grillage, showing the flexible fabric attached to and supported from it. 70

In the drawings, 2 represents the apparatus employed for feeding the plastic concrete through suitable pipes 3 to the form resting upon the piling beneath the surface of the water. This method, employed quite generally in subaqueous construction, is known as the "Tremie" system. The piles 4 having been driven in the usual way, are cut off below the surface of the water 80 at the desired grade or level and the form 5 is lowered until it rests on the top of the piling. This form is preferably divided by partitions 7 into a series of spaces or chambers, the walls of which confine the plastic 85 concrete and prevent it from flowing out and becoming absorbed by the water. The concrete flowing down through the pipe 3 under a head equal to the height of the column of cement will work upwardly from 90 the bottom, as indicated in Fig. 2, and being confined by the walls and partitions of the form will gradually fill the form without exposing the concrete to the washing action of the water while being deposited, 95 as plainly shown in Fig. 2.

The bottom of the form is open and provided with a grillage consisting, preferably, of bars 8 and 9 arranged longitudinally and transversely, (though any other arrangement may be employed) and secured by suitable means to the walls and partitions of the form and resting, when the form is lowered to its proper position, upon the upper ends 100 of the piles or other supports. Beneath the grillage I provide a means for retaining the concrete until it is set, comprising a flexible fabric of suitable material, consisting, preferably, of an upper wire mesh 10, a lower 105 or outer mesh 11 and an intermediate flexi- 110

ble canvas or cloth 12, the whole being secured to the bars of the grillage in such a way that the fabric will sag or hang down in loops below the bars of the grillage, as 5 plainly indicated in Fig. 2, the loops depending between the upper ends of the piles or other supports and hugging the surface of the piles, as shown in Fig. 5. When the plastic concrete is allowed to flow down into 10 the form it will pass down between the bars of the grillage and fill the sagging loops of the fabric and cause them to hug the upper ends of the piles or supports, and when the concrete has become set the piles or other 15 supports will be securely locked against oscillation and the grillage bars resting on the tops of the piles or supports will be concealed and protected against the deteriorating action of the water or agencies therein. 20 In time the fabric exposed to the water may rust or wear away, but this will be immaterial, as the concrete will then have set and the fabric will have served its purpose as soon as the concrete has become hardened 25 sufficiently to remain in place around the upper ends of the piles or supports. The depending portions of the concrete bed will not only lock the piles or other supports against oscillation, but the bed will be securely locked on the piles or supports against 30 displacement from any cause.

The introduction of the concrete into the form fills the flexible bottom, causing it to sag at all points and conform to the pile 35 heads or other supports and makes it possible to provide a suitable foundation on which to rest sub-aqueous foundations or superstructures, particularly where certain grades are desirable and the natural 40 sub-aqueous formation is irregular and unstable in its nature. It will also be found valuable in structures resting on piling or other supports above the water.

The form may be divided into areas of 45 any suitable size, according to the local conditions, and the grillage may be composed of bars of any suitable size and arranged a suitable distance apart, according to the character of the foundation and the load.

50 I do not wish to be confined in this application to the arrangement of the partitions in the form or the arrangement of the grillage bars with respect to one another, or the material employed for retaining the plastic 55 concrete until it has set around the bars and the head of the piling or other support, as various modifications will suggest themselves to any one skilled in this art and still be within the scope of my invention.

I claim as my invention:—

1. A sub-aqueous foundation including in combination a series of piles, a form supported thereby, and having a grillage bottom, a fabric supported by said grillage bottom, and concrete filling said form, said fabric being so disposed relative to said grillage bottom that the concrete supported by the fabric passes through the grillage bottom and surrounds the head of each pile, thereby locking said piles against oscillation when said concrete has set. 60

2. A sub-aqueous foundation including in combination a series of piles, a form supported thereby, and having a grillage bottom composed of metal bars resting upon the upper ends of said piles, a fabric supported by said grillage bottom, and concrete filling said form, said fabric being so disposed relative to said grillage bottom that the concrete supported by the fabric passes through the grillage bottom and surrounds the head of each pile, thereby locking said piles against oscillation when said concrete has set. 70

3. A sub-aqueous foundation including in combination a series of piles, a form supported thereby and having a grillage bottom, a flexible fabric consisting of an upper and lower wire mesh, and an intermediate suitable textile mesh, and concrete filling said form and resting on said fabric, said fabric being so disposed relative to said grillage bottom that the concrete supported by the fabric passes through the grillage bottom and surrounds the head of each pile, thereby locking said piles against oscillation when the concrete has set. 80

4. A sub-aqueous foundation, including in combination a series of piles, a grillage composed of metal bars resting upon the flattened upper ends of said piles and supported thereby, a form inclosing said grillage and comprising upright side and end walls, a flexible fabric suspended in loops from said grillage bottom, said flexible fabric 100 consisting of an upper and lower wire mesh, and an intermediate suitable textile mesh, and concrete filling said form, and extending through said grillage bottom into contact with said fabric, whereby said concrete 105 is provided with pockets engaging and surrounding the upper end of each pile. 110

In witness whereof, I have hereunto set my hand this 20th day of March, 1912.

WALTER BUTLER.
